US00D589665S

(12) **United States Design Patent**
Kwapis

(10) **Patent No.:** **US D589,665 S**
(45) **Date of Patent:** **** Mar. 31, 2009**

(54) **SPONGE**

(75) Inventor: **Alex Kwapis**, Columbus, OH (US)

(73) Assignee: **Mary Kay Inc.**, Dallas, TX (US)

(**) Term: **14 Years**

(21) Appl. No.: **29/321,183**

(22) Filed: **Jul. 11, 2008**

(51) LOC (9) Cl. **04-01**

(52) U.S. Cl. **D32/40**; D28/7

(58) **Field of Classification Search** D32/40-45;
15/244.1-244.4, 209.1; D28/7, 8, 8.1, 8.2,
D28/63

See application file for complete search history.

(57) **CLAIM**

The ornamental design for a sponge, as shown and described.

DESCRIPTION

FIG. 1 is a top front perspective view of my design;

FIG. 2 is a front view of my design;

FIG. 3 is a back view of my design;

FIG. 4 is a right side view of my design;

FIG. 5 is a left side view of my design;

FIG. 6 is a top view of my design; and,

FIG. 7 is a bottom view of my design.

All other surface(s) or portion(s) of my design not shown in the figures or otherwise described in the specification form no part of the claimed design.

1 Claim, 2 Drawing Sheets
